Attorney

UNITED STATES PATENT OFFICE.

CHARLES F. THATCHER, OF PROVIDENCE, RHODE ISLAND.

BOTTLE STOPPER.

1,418,035.

Specification of Letters Patent. Patented May 30, 1922.

Application filed September 7, 1920. Serial No. 408,468.

To all whom it may concern:

Be it known that I, CHARLES F. THATCHER, a citizen of the United States, residing at Providence, in the county of Providence and 5 State of Rhode Island, have invented new and useful Improvements in Bottle Stoppers, of which the following is a specification.

This invention relates to certain new and useful improvements in bottle stoppers, and 10 relates more particularly to the rubber stopper itself, which latter is commonly employed in connection with bails and eccentricities, so as to close the bottle.

The primary object of the invention is to 15 provide a loop structure which is embedded into the rubber of the stopper during the process of the manufacture thereof.

A further object of the invention is to provide means whereby the loop will be effectively related to or secured in the rubber 20 of the stopper, so as to prevent pulling out or other movement of the loop with relation to the stopper.

Still further, the invention aims to provide 25 a simple and economical form of loop structure, and to also provide an integral part of the rubber body which passes through a part of the loop so as to more effectively anchor the loop.

30 Further and other objects will be later set forth and manifested in the course of the following description.

Figure 1 is a longitudinal sectional view of the preferred form of the invention.

35 Figure 2 is a similar view of a modified form;

Figure 3 is a similar view of a further modified form of the invention;

Figure 4 is a view taken on line 4—4 of 40 Figure 3;

Figure 5 is a plan view of the washer of Figure 1; and

Figure 6 is a similar view of the washer of Figure 2.

45 In proceeding in accordance with the present invention the stopper is formed with a body 1, top flange 2, and an upper reinforcing disk 3, which latter also serves as a washer seat. In the preferred form a piece 50 of wire is employed bent between its ends to form a loop or eye 4 through which the usual bail of the fastener proper extends.

A washer 5 seats on the disk 3 and acts as a 55 wear surface, upon which the bail operates during compression of the rubber incident to locking of the stopper. The ends of the

wire are then reversely curved in opposite directions as indicated at 6 to form an eye or loop 7, the wire terminals 8 extending in opposite direction as shown in Figure 1. 60 This loop structure is molded in the rubber body so that an integral part 9 of the latter will extend through the loop 7, this integral part being connected at its ends to the rubber body. In addition the disk 3 will have a 65 part 10 which extends across the bottom of the eye or loop 4, and since the ends 8 also project into the body of the rubber it will be seen that the loop structure will be firmly anchored to the said body. In this form 70 of the invention the washer 5 is formed with a large circular eye 11 so as to completely receive the loop 4 in any position of eye 11.

In Figure 2, a single loop structure is employed and in which a single piece of wire 75 is bent to form an ovaloid loop 11^a, the wire terminals 12 extending outwardly in opposite directions and into the body of the rubber. In this form it will be seen that an integral part 13 of the rubber body similar 80 to part 9 in Figure 1 is provided, with the exception that the part 13 does not occupy the entire loop, leaving the upper part thereof open to receive the bail of the fastener. The part 13 extends flush with the top of 85 disk 3. In this form a washer 14 is or may be employed having an elongated hole 15 which receives the bail 11.

Figures 3 and 4 show a sheet metal or other flat piece of metal which is indicated at 90 16 and has eyes 17 and 18 punched out or otherwise formed at its top and bottom. The lower end of the metal plate is split at 19 and the resultant parts 20 are turned outwardly at right angles and in opposite directions. In this form it will be seen that the ends 20 are embedded in the rubber body 95 and the latter has an integral part 21 which extends through the eye 18 similar to the part 9 in Figure 1. Also in this form a 100 somewhat ovaloid cross-section metal ring 22 is employed which encircles the disk 3 and seats on the flange 2, so as to provide a wearing surface on and against which the bail of the locking fastener exerts its force. 105

From the foregoing it will be seen that in each form of the invention a loop structure is provided which has a bail receiving eye, oppositely extending ends or feet embedded in the rubber body, and an integral part of the 110 rubber body connected at each end thereto and extending through the loop structure,

thus in each instance effecting positive and certain securement or anchorage of the loop structure within the rubber body. In actual practice it has been found that it is impossible to remove the loop structure from the rubber body without cutting or destroying the latter.

Having thus described my invention, what I claim as new and desire to secure by Letters Patent is:

1. In a bottle stopper, a rubber body, and a loop structure having a body portion provided with a bail receiving eye in its upper end and having an eye-like part in its lower end spaced from the bail-receiving eye, said loop structure being embedded in the rubber body and an integral part of the latter extending through the eye-like part in the lower end of the loop structure and for a distance below the latter.
2. In a bottle stopper, a rubber body, and a loop structure having a body portion provided with a bail receiving upper eye and having a lower eye-like part, said loop structure having parts below the lower eye-like part which extend in opposite directions and are completely embedded in the rubber body and the latter having an integral part which extends through the lower eye-like part and for a distance below the latter.
3. In a bottle stopper, a rubber body and a loop structure having its lower end completely embedded in the body and having an eye with a pair of oppositely extending parts at the bottom of the eye, said body having an integral part extending through the eye and said oppositely extending parts being

completely embedded in the rubber body and located above the bottom of the rubber body.

4. In a bottle stopper, a rubber body and a loop structure consisting of a metal plate having a pair of eyes formed therein, the lower end of the plate being embedded in the body and arranged above the bottom of the body and with an integral part of the latter extending through the lower eye, and projections borne by the plate and extending laterally therefrom and completely embedded in the rubber body.

5. In a bottle stopper, a rubber body, and a flat metal plate having an upper and a lower eye, the upper eye extending beyond the body and an integral part of the latter extending through the lower eye, the lower end of said plate being bifurcated, and the bifurcations extending in opposite directions and embedded in the rubber body.

6. In a bottle stopper, a rubber body having an upwardly extending reinforced part of less diameter than that of the body, an apertured washer associated with said reinforced part and having its upper face extending thereabove, and a loop structure having its upper end extending through the aperture of the washer and having its lower end embedded in the rubber body.

In testimony whereof I have signed my name to this specification in the presence of two subscribing witnesses.

CHARLES F. THATCHER.
